 business as F. H. Maloney Company, Houston,
 Tex.

Application March 26, 1949, Serial No. 1,644

Term of patent 3½ years

(Cl. D23—1)

To all whom it may concern:

Be it known that we, Waldemar J. Coliz and Eugene E. Eutsler, Jr., citizens of the United States of America, residing at Houston, in the county of Harris and State of Texas, have invented a new, original, and ornamental Design for a Cream Separator for Milk Bottles, of which the following is a specification, reference being had to the accompanying drawing, forming a part thereof.

Fig. 1 is a front elevational view of a cream separator for milk bottles showing our new design.

Fig. 2 is a bottom plan view,

Fig. 3 is a side elevational view taken at right angles to Fig. 1 and taken partially in section on line 3—3 of Fig. 1, and

Fig. 4 is a top plan view thereof.

We claim:

The ornamental design for a cream separator for milk bottles, as shown.

WALDEMAR J. COLIZ.

EUGENE ERNEST EUTSLER, JR.
